CLAIM

The ornamental design for a confectionery as shown and
described.

DESCRIPTION

The file of this patent contains at least one drawing/photograph
executed in color. Copies of this patent with color
drawing(s)/photograph(s) will be provided by the Office
upon request and payment of the necessary fee.

FIG. 1 is a front, top, and right perspective view of a
confectionery showing our new design;

FIG. 2 is a front, bottom, and right side perspective view
thereof;

FIG. 3 is a front elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The broken lines shown in FIGS. 3–7 illustrate environment
and form no part of the claimed design.
